(57) **CLAIM**

The ornamental design for a scuba tank backplate, as shown and described.

DESCRIPTION

FIG. 1 is a front perspective view of a scuba tank backplate embodying my new design with an attached harness system, wherein the attached harness system is shown in broken lines for illustrative purposes only and forms no part of the claimed design;

FIG. 2 is a front elevational thereof;

FIG. 3 is a side view thereof, the opposite side being a mirror image thereof;

FIG. 4 is a rear view thereof;

FIG. 5 is a top view thereof; and,

FIG. 6 is a bottom view thereof.
